UNITED STATES PATENT OFFICE

126,486

DESIGN FOR A DRESS ENSEMBLE

Samuel Riesenber, New York, N. Y.

Application November 12, 1940, Serial No. 96,507

Term of patent 3½ years

To all whom it may concern:

Be it known that I, Samuel Riesenber, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my new design.

Fig. 2 is a rear view of Fig. 1.

Fig. 3 is a front view of the dress member of the ensemble, and

Fig. 4 is the rear view thereof.

I claim:

The ornamental design for a dress ensemble, substantially as shown.

SAMUEL RIESENBERG.
